ROBERT ROGER BOTTOMS, OF LOUISVILLE, KENTUCKY, ASSIGNOR TO THE HELIUM COMPANY, OF LOUISVILLE, KENTUCKY, A CORPORATION OF KENTUCKY

PROCESS FOR EXTRACTING HELIUM

Application filed May 13, 1930. Serial No. 452,020.

This invention relates to the separation of helium from other gases which have boiling points, at atmospheric pressure, above the critical temperature of helium. The invention is likewise applicable to the separation of neon from the same kind of gases, and therefore for the purposes of this invention, neon is to be considered as the equivalent of helium.

10 The main object of the present invention is to effect the separation and removal of the helium, in a substantially pure state and as a single step, as distinguished from previous processes in which expansion, rectification, 15 recompression and other such series of steps are employed.

In commercial practice it is customary after extracting the helium to store it in steel cylinders under comparatively high pressure, 20 for instance 2000 pounds per square inch.

This invention is an improvement on that disclosed in my previous Patent 1,821,540, issued Sept. 1, 1931, in which crude helium is circulated in a closed cycle in two pressure 25 stages, both substantially above that of the atmosphere, and the pure helium is withdrawn from the higher pressure stage of the cycle in gaseous form and substantially helium-free liquid is withdrawn from the cycle from the lower pressure stage, the cycle being 30 continuously replenished by the addition of further mixture from which the helium is to be extracted.

In the specific embodiment disclosed in 35 said patent, this mixture is first compressed and largely if not completely liquefied and the crude helium separated therefrom for circulation in said cycle.

My present invention is an improvement 40 and simplification of that specifically disclosed in said patent in that I add the mixture in gaseous state directly to the crude helium gas in the cycle, and liquefy all of the non-helium constituents in the cycle instead of 45 before they enter the cycle. Thus I may use gases containing a very low percentage of helium and the percentage in the crude helium is gradually built up to a concentration where 50 only a portion of the helium will go into solution upon the liquifying of the readily lique-

fiable portions of the crude helium under high pressure in the cycle, and pure helium gas may be directly separated at high pressure and delivered for storage. Thus all of the compression may take place solely in the crude helium 55 cycle and the necessity for separate compression of the gaseous mixture serving as the source of supply is avoided.

Other objects, advantages and important features of my invention will be pointed out 60 hereinafter or will be apparent from a consideration of the following description and the accompanying drawing showing a preferred embodiment.

As an example of the gas which may be 65 treated by my process, I may mention a natural gas which after the removal of all carbon dioxide and water, has the following composition: helium 2%, methane 20%, ethane 2% and nitrogen 76%. Any other helium 70 containing gas freed of carbon dioxide and water vapor may be used.

In the drawing, the single view is a vertical sectional view of one form of the apparatus embodying the invention and adapted for 75 carrying out my improved process, many of the parts being somewhat conventionally illustrated.

In the form shown, the natural gas in which the helium forms a relatively small 80 proportionate part, is delivered through the pipe 22 to a multiple stage compressor where it is compressed to approximately the pressure required for both separation and storage. This may be approximately 2,000 pounds. 85 The compressed gas is delivered through the pipe 18 and a suitable cooler 25 where the heat of compression is removed. The gas is then delivered through the pipe 4 in a heat interchanger 1, thence through a pipe 11 to a 90 coil 6 in the chamber 3 of a condenser 7, to a collecting pot or chamber 15 in the lower part of the condenser.

It must be understood at this point that the 95 operation has just started, and that the pressure is gradually built up to this point by a compressor 23.

When the pressure in the parts before named has reached a value of approximately 2000 pounds, valve 8 is opened and the gas is 100

allowed to escape through valve 8 in sufficient quantities to maintain the pressure within pipes 18 and 4, coil 6 and chamber 15, at the approximate value of 2000 pounds. In 5 throttling the gas from the high pressure through valve 8 it suffers a drop in temperature by the well known Joule-Thompson effect. From receiver 2 the cooled gases pass through valve 9 and pipe 12 through chamber 3 of condenser 7, and thence through pipes 10 and passage 5 in heat interchanger 1, and to the atmosphere, or when it is desired to save the gas, into a pipe line through pipe 19. The gases which have been cooled by the 15 Joule-Thompson effect in throttling through valve 8, in their passage through the heat interchanger 1, counter-current to the ingoing gas in pipes 4, take up the heat from the ingoing gases in pipe 4, and cool these gases 20 to a lower temperature.

Subsequently the gases flowing through pipe 11, coil 6 and chamber 15, reaching valve 8, have already been cooled to a low temperature and thus suffer a further drop in temperature until a point is finally reached where the gases other than helium reach the liquefaction point, which for nitrogen is approximately minus 195° C. During this preliminary cooling period valve 24 remains closed, 25 preventing the escape of the gases through valve 24 and pipe 20. When this point is reached, gases will be liquefied in coil 6 and chamber 15, and since the helium content of the gas is only 2% the helium itself will be 30 carried in the liquid, that is, in solution with the other liquefied gases. When this liquid is then throttled through valve 8 into the chamber 2, due to the reduction in pressure, most of the helium in solution will be given off and 35 the pressure of the liquid in receiver 2 will be maintained at the proper operating point by manipulation of valve 9. This proper operating point is preferably between 50 and 200 pounds pressure. At the valve 9 the pressure 40 may drop to substantially that of the atmosphere. A valve 26 in the pipe 16 serves to maintain the desired pressure in the chamber 2, and the delivery of the crude helium to the compressor at low pressure.

50 The helium content in the gas will pass out through pipe 17, thence through pipe 13 in heat interchanger 1 and pipe 16, past valve 26, back to the intake of the compressor where it is mixed with a further supply of the incoming natural gas. It will be seen that the 55 amount of helium in the gas being compressed by compressor 23 will thus gradually increase in value until the point is reached where the gas entering the apparatus contains an 60 amount of helium in excess of the saturation point for the liquefied gases. When this point is reached, namely, approximately 3% helium, all the helium in excess of about 3% will 65 pass into pipe 14. Valve 24 is then partially open, sufficient to regulate the flow of helium

into pipe 20 and thence to storage. When this point is reached the apparatus is then in normal operation, and the gases being throttled through valve 8 into receiver 2 carry in solution approximately 3% by volume of helium. All of this helium, with the exception of probably $\frac{1}{10}\%$ to $\frac{2}{10}\%$ will be given off from the liquid and passed out through pipe 17 as the liquid is being continuously drawn from receiver 2 through valve 9 and pipe 12 into chamber 3 of condenser 7.

These liquefied gases will then surround chamber 15 and coil 6, forming the necessary refrigeration for condensing the gases in coil 6. Part of the liquids in compartment 3 will then be vaporized and the vaporized gas, together with any excess liquid, will pass through pipe 10 and through the heat interchanger in passages 5, giving up their refrigeration to the ingoing gases.

It will be noted that there is no drop in pressure between the compressor and the manifold 20 except such as is due to flow resistance and the pure helium is separated and stored by the use of a single compressor and without either substantial drop in pressure or the necessity for any recompression. For the purposes of this invention helium is considered pure if it does not contain over 10% of other gases.

The apparatus is so controlled that the pot 15 may be kept immersed in liquid and the coil 6 may also be kept immersed in liquid, or a lower level of liquid may be maintained as desired. In any event the coil 6 and the pot 15 are kept at a temperature which is that produced by the boiling or evaporating of the non-helium constituents of the gas under low pressure existent in the chamber 3. This temperature is sufficient to liquefy substantially all of the non-helium constituents of the original gas in the coil 6 and pot 15, due to the fact that within the coil and pot the pressure is very high. The gases produced in the chamber 3 pass through the pipe 10 to the chamber 5 of the heat interchanger, from which they pass out through the pipe 19.

It will, of course, be understood that the drawing shows only a conventional representation of a heat interchanger and that the various pipes 13, 4 and 14 may be in the form of coils or zigzag passages in order to utilize to the maximum extent the low temperature of the outgoing gases to cool down the ingoing gases in the pipe 4.

All of the helium in excess of 3% will pass out through the pipe 14 in unliquefied form, and this 3% will separate out in the receiver 2 as crude helium containing 50% to 70% of helium, and go back to the compressor for recirculation, so that substantially all of the helium is recovered from the original gas, and the helium delivered to the storage passages 21 is of commercial pu-

riety. By commercial purity I mean containing less than 10% of other gases. As above noted, the loss of helium is only $\frac{1}{10}$ % to $\frac{2}{10}$ %. The percentage of helium in the crude helium will vary with the pressure in the chamber 2.

My improved process makes possible the separation of the helium in a commercially pure state in one step and the storage of the separated helium under the pressure of 10 the compressor which supplies the crude gas.

The receiver 2, instead of serving for the separation of the crude helium gas as in the apparatus disclosed in my Patent 1,821,1540, serves, in the present process, merely for 15 the release of the helium in solution. This portion of the helium is not lost, but is vented to the intake of the compressor and recirculated.

The pot 15 provides for the separation of 20 all of the liquids from the pure helium instead of separation of liquefied gas from the recompressed crude helium mixture, as in the prior application above referred to.

It will be noted that in my invention there 25 is a continuous cyclic flow of crude helium fluid. The crude helium gas flows from the receiver 2, through pipes 17, 13 and 16, to the compressor, thence through pipes 18 and 4 and coil 6, to the pot 15. Here the gaseous 30 impurities become liquefied and are delivered to the receiver 2 under lower pressure, and the crude helium escapes from the liquid as it is passed into the receiver.

The cycle involves two pressure phases, 35 the higher pressure from the compressor to the valve 8, and the lower pressure from the valve 8 back to the compressor. Pure helium is continuously withdrawn from the cycle through pipe 14 and substantially helium 40 free liquid is continuously withdrawn from the cycle through the pipe 12. Makeup fluid is admitted to the cycle through the pipe 22.

If the gas delivered through the pipe 22 contains less than 3% of helium, all of this 45 helium may be dissolved in the liquid in the pot 15 and pass through to the receiver 2. The percentage of helium flowing out through the pipe 17 will be very much higher than that admitted through the pipe 22, so 50 that the percentage of helium in the gas liquefied in the coil 6 will continuously increase until it exceeds 3%, and then the excess will remain as a free gas in the pot 15, and may flow out through the pipe 14.

55 Thus the apparatus may be operated until a concentration is arrived at where free helium may be drawn off, and the plant thereafter may be continuously operated under substantially uniform conditions.

60 The amount of helium flowing out through the pipe 14 will equal the amount in the crude mixture delivered in through the pipe 22.

If the mixture to be treated contains a 65 comparatively high percentage of helium, for example 3% or more, there may be sepa-

ration in the pot 15 from the beginning of the operation when the temperature of liquefaction of the impurities has been reached. Of course, if the percentage of helium in the gas treated is below $\frac{1}{10}$ %, the process 70 will not operate at the pressures stated, because of the solubility of that amount of helium in the liquid in the receiver 2.

The improved apparatus illustrated is disclosed and claimed in my copending divisional application Serial No. 546,244, filed 75 June 23, 1931.

Having thus described my invention, what I claim as new and desire to secure by Letters Patent is:

1. The method of separating helium from a gaseous mixture, including circulating a crude helium mixture in a continuous cycle having two pressure stages, at least the higher stage being substantially above that of the atmosphere, separating substantially pure helium from liquid containing helium in the higher pressure stage and withdrawing it from the cycle, separating substantially helium-free liquid from crude helium gas in the lower pressure stage and withdrawing it from the cycle, utilizing said helium-free liquid at a still lower pressure to liquefy gases in said higher pressure stage of said cycle, and replenishing said cycle by adding 85 said gaseous mixture containing helium to the crude helium gas in the lower pressure stage of said cycle.

2. The method of separating helium from a gaseous mixture, including circulating 100 crude helium mixture in a continuous cycle having two pressure stages, the upper pressure stage being approximately 2000 pounds per square inch and the lower pressure stage being substantially below that of the higher 105 pressure stage, cooling said mixture and thereby separating substantially pure helium from liquid containing helium in said higher pressure stage, withdrawing said pure helium from the cycle under said pressure of approximately 2000 pounds, separating substantially helium-free liquid from crude helium gas in the lower pressure stage and withdrawing said liquid from the cycle, and replenishing said cycle by adding said gaseous mixture containing helium to said crude helium gas at approximately the point in the cycle where said crude helium gas is raised from said lower to said higher pressure.

3. The method of separating helium from a gaseous mixture, including circulating a crude helium mixture in a continuous cycle having two pressure stages, cooling the crude helium in the higher pressure stage to liquefy substantially all of the mixture other than helium, withdrawing from the cycle the unliquefied substantially pure helium, delivering the liquid to the lower pressure stage of the cycle, separating substantially helium-free liquid from crude 120

helium gas in said lower pressure stage of the cycle, adding to the crude helium gas further quantities of the gaseous mixture to be separated, returning the same to the higher pressure stage of the cycle, and evaporating the substantially helium-free liquid to effect said liquefaction.

Signed at Louisville, in the county of Jefferson and State of Kentucky, this 7th day of May, A. D. 1930.
